UNITED STATES PATENT OFFICE.

ARTHUR LONGWORTH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

DESIGN FOR A RADIO RECEIVING LOOP.

Application filed October 23, 1926. Serial No. 19,450. Term of patent 3½ years.

To all whom it may concern:

Be it known that I, ARTHUR LONGWORTH, a citizen of the United States, residing at Rochester, in the county of Monroe and State of New York, have invented a new, original, and ornamental Design for Radio Receiving Loop, of which the following is a specification, reference being had to

the accompanying drawing, forming part thereof.

The figure is a perspective view of a radio receiving loop showing my new design.

I claim:

The ornamental design for a radio receiving loop as shown.

ARTHUR LONGWORTH.
